WHEELED ANIMAL FIGURE TOY

Maurice Meth, Bronx, N. Y.

Application March 20, 1950, Serial No. 150,677

6 Claims. (Cl. 280—47)

1

This invention relates to new and useful improvements in toys, and, more particularly, a wheeled toy on which a child can ride.

One object of the invention is the provision of a wheeled animal figure toy on which a child can ride, and which has imparted to it by the rotation of its wheels a hopping motion peculiar to the animal which it represents.

Another object of the invention is the provision of means whereby the rider can steer the toy.

Still another object of the invention is to construct the toy so that only the rear portion thereof is moved up and down to provide the hopping motion.

A still further object of the invention is the provision of means whereby the toy can either be pushed or pulled along by a person other than the rider.

For further comprehension of the invention, and of the objects and advantages thereof, reference will be had to the following description and accompanying drawings, and to the appended claims in which the various novel features of the invention are more particularly set forth.

In the accompanying drawings forming a material part of this disclosure:

Fig. 1 is a side elevational view of the toy of the invention.

Fig. 2 is a plan view of the chassis of the toy with the animal figure removed.

Fig. 3 is a sectional view of the chassis on line 3—3 of Fig. 2.

Fig. 4 is a sectional view of the chassis on line 4—4 of Fig. 2.

Fig. 5 is a fragmentary view from beneath the front end of the chassis.

Fig. 6 is a view similar to Fig. 5 but with the mechanism concerned with steering the toy in an altered position.

Fig. 7 is a fragmentary sectional view on line 7—7 of Fig. 2.

Fig. 8 is a fragmentary sectional view on line 8—8 of Fig. 4 showing the crank turned 180°.

Fig. 9 is a side elevational view similar to Fig. 1 but illustrating means for pushing the toy.

The wheeled toy, according to the first form of the present invention illustrated in Figs. 1 to 8, includes a stuffed animal 10 such as a horse, provided with a saddle 11 and stirrups 12 for supporting a child thereon. A steering column 13 projects upwardly through the rear of the animal's head and has secured to its upper end a handle bar 14 of ordinary construction.

2

The legs 15 of the animal are mounted on substantially parallel front to rear strap metal frame members 16 of the chassis of the toy, see also Fig. 2. At their front ends, see Fig. 3, the frame members 16 are secured by bolts 17 to a cross piece 18 whose ends are turned down and secured by bolts 20 to the upturned ends of a second cross piece 21. Also secured to the cross piece 21 are the front ends of the main chassis frame members 22 which at their rear ends are joined together by a cross bar 23, and have the rear axle 24 journaled therein.

Referring now to Figs. 2, 3, 5 and 6 the cross piece 21 has pivoted centrally thereto by a bolt 15 25 a longer cross member 26 in whose downturned ends the front axle 27 is journaled. Preferably a washer 29 is provided between members 21 and 26. Wheels 28 of any suitable sort are secured on the outer ends of the front and rear axles 27 20 and 24 preferably by squaring the ends of the axles. On either side of the pivot bolt 25 the cross member 26 has pivoted thereto in any suitable manner such as by rivets 30, a rearwardly extending steering frame member 31. The frame 25 members are pivoted at their rear ends to a cross piece 32. Located above the cross piece 32 is another cross bar 33 secured at its ends to the main frame members 22 and having the steering column 13 journaled in the center thereof. The lower end of said column is squared as best shown 30 at 34 in Fig. 7 and is fixed in the center of steering frame cross piece 32. A cotter pin 35 is provided to prevent the column 13 from being pulled up out of engagement with the cross piece 32.

The construction is such that normally the front wheels 28 are in the position of Fig. 5 to provide straight line travel of the toy, but by turning the handle bar 14 and thereby the steering column 13, the cross piece 32 is shifted to a position such as that shown in Fig. 6 which by means of the frame members 31 shifts the cross member 26 and thereby the wheels 28 to the turning position of Fig. 6. Thus, the toy can be steered by the rider thereof through the medium of the handle bar 14.

Means is provided for limiting pivoting of the cross member 26 in either direction for preventing the front wheels 28 from being turned too far under the wheeled toy unbalancing the front end thereof resulting in the toy spilling its rider. That means is characterized by pins 22^a, see Figs. 2, 3 and 5 to 7, which depend from the bottom face of the main frame members 22 in the path of pivotal movement of the cross member 26. 55 When the cross member 26 is pivoted in either

direction it strikes one of the pins 22^a, see particularly Fig. 6, limiting pivotal movement of the cross member 26 in that direction.

In the simplest form of the invention the toy may be provided with a pull rope 36 attached to cross piece 18 by means of a hole 37 provided therein, see Figs. 1 and 2, so that the toy, with a child seated thereon, can be pulled along by a second person.

In order that the animal 10, here shown as a horse, can be provided while the same is traveling along on the wheels 28 with a gait similar to that of a horse, the following means are provided.

The rear axle 24, as described hereinbefore, is journalled in the main frame members 22 and has a wheel 28 secured on either end thereof. The ends of the rear axle 24 are rotatively extended through tubular bushings 38 fixedly mounted through the frame members 22, as shown in Figs. 4 and 8. The axle 24 is offset just inside the frame members to provide a crank, and the offset portion has journalled thereon a pair of connecting rods 40 pivoted each to the inverted U-shaped portions of a one-piece cross frame member 41 by a bolt 42, see also Fig. 8.

The ends of the frame member 41, exteriorly of the connecting rods 40, have secured thereto the rear ends of the front to rear frame members 16, which it will be remembered are the ones on which the legs 15 of horse 10 are secured.

The construction is such that members 41 comprise a reciprocating frame moved up and down by the connecting rods 40 as the rear axle 24 rotates.

It will be seen therefore, that as the toy rolls along on wheels 28 the rotation of rear axle 24 will reciprocate the rear portion of the horse up and down through the connecting rods 40, the frame members 41 and 16 and rear legs 15, so that a hopping motion similar to the gait of a horse is imparted to the horse-like figure 10.

In the modification of the invention shown in Fig. 9, the toy is provided with a handle whereby it can be pushed about rather than pulled as in the previous form of the invention. The toy is illustrated as having a tubular handle 44 similar to that of a baby carriage, the ends of the handle being flattened as at 45 and secured to the frame bars 22. Struts 46 having one end secured to handle 44 and the other to frame bar 23 preferably are provided to brace the handle.

While I have illustrated and described the preferred embodiments of my invention, it is to be understood that I do not limit myself to the precise constructions herein disclosed and the right is reserved to all changes and modifications coming within the scope of the invention as defined in the appended claims.

Having thus described my invention, what I claim as new, and desire to secure by United States Letters Patent is:

1. A toy on which a child can ride comprising an animal figure, a frame on which said figure is secured, said frame being reciprocable up and down at its rear end to reciprocate the rear portion of the figure up and down and comprising a pair of front to rear members, a cross frame member connecting the rear ends of said front to rear members, a main frame on which the first mentioned frame is mounted at its front end, an auxiliary steering frame pivotally secured to said main frame at the forward end of the latter, a rear axle journalled in said main frame, a front axle journalled in said auxiliary

frame, wheels secured on the ends of said axles, steering means including a steering column secured to said auxiliary frame and projecting through the said figure, and a handle bar secured on the upper end of the column, and means actuated by the rotation of the rear wheels to reciprocate the rear end of the figure supporting frame up and down.

2. A toy on which a child can ride comprising an animal figure, a frame on which said figure is secured, said frame being reciprocable up and down at its rear end to reciprocate the rear portion of the figure up and down and comprising a pair of front to rear members, a cross frame member connecting the rear ends of said front to rear members, said cross frame member having spaced inverted U-shaped members, a main frame on which the first mentioned frame is mounted at its front end, an auxiliary steering frame pivotally secured to said main frame at the forward end of the latter, a rear axle journalled in said main frame, a front axle journalled in said auxiliary frame, wheels secured on the ends of said axles, steering means including a steering column secured to said auxiliary frame and projecting through the said figure, and a handle bar secured on the upper end of the column, and means actuated by the rotation of the rear wheels to reciprocate the rear end of the figure supporting frame up and down, said reciprocating means including a crank-like offset portion of said rear axle and a pair of connecting rods journalled on said offset portion and pivoted to and working between the arms of the U-shaped portions of said cross frame member.

3. A toy on which a child can ride comprising an animal figure, a frame on which said figure is secured, said frame being reciprocable up and down at its rear end to reciprocate the rear portion of the figure up and down and comprising a pair of front to rear members, a cross frame member connecting the rear ends of said front to rear members, a main frame on which the first mentioned frame is mounted at its front end, said main frame comprising a pair of front to rear members, and front and rear lateral members and a substantially centrally disposed lateral member connecting said front to rear members, an auxiliary steering frame pivotally secured to the center of said front lateral member, a rear axle journalled in the front to rear members of the main frame, a front axle journalled in said auxiliary frame, wheels secured on the ends of said axles, steering means including a steering column secured to said auxiliary frame and projecting through the said figure, and a handle bar secured on the upper end of the column, and means actuated by the rotation of the rear wheels to reciprocate the rear end of the figure supporting frame up and down.

4. A toy on which a child can ride comprising an animal figure, a frame on which said figure is secured, said frame being reciprocable up and down at its rear end to reciprocate the rear portion of the figure up and down and comprising a pair of front to rear members, a cross frame member connecting the rear ends of said front to rear members, said cross frame member having spaced inverted U-shaped members, a main frame on which the first mentioned frame is mounted at its front end, said main frame comprising a pair of front to rear members, and front and rear lateral members and a substantially centrally disposed lateral member connecting said front to rear members, an auxiliary steering frame

pivots to the center of said front lateral member, a rear axle journalled in the front to rear members of the main frame, a front axle journalled in said auxiliary frame, wheels secured on the ends of said axles, steering means including a steering column secured to said auxiliary frame and projecting through the said figure, and a handle bar secured on the upper end of the column, and means actuated by the rotation of the rear wheels to reciprocate the rear end of the figure supporting frame up and down, said reciprocating means including a crank-like offset portion of said rear axle and a pair of connecting rods journalled on said offset portion and pivoted to and working between the arms of the U-shaped portions of said cross frame member.

5. A toy on which a child can ride comprising an animal figure, a frame on which said figure is secured, said frame being reciprocable up and down at its rear end to reciprocate the rear portion of the figure up and down and comprising a pair of front to rear members, a cross frame member connecting the rear ends of said front to rear members, said cross frame member having spaced inverted U-shaped members, a main frame on which the first mentioned frame is mounted at its front end, said main frame comprising a pair of front to rear members, and front and rear lateral members and a substantially centrally disposed lateral member connecting said front to rear members, an auxiliary steering frame pivotally secured to the center of said front lateral member, and including a front member pivoted centrally to the main frame front member, a second located below the centrally disposed lateral member of the main frame, and connecting links between the ends of said second member and said auxiliary frame front member, a rear axle journalled in the front to rear members of the main frame, a front axle journalled in said auxiliary frame, wheels secured on the ends of said axles, steering means including a steering column secured to said auxiliary frame and projecting through the said figure, and a handle bar secured on the upper end of the column, and means actuated by the rotation of the rear wheels to reciprocate the rear end of the figure supporting frame up and down, said reciprocating means including a crank-like offset portion of said rear axle and a pair of connecting rods journalled on said offset portion and pivoted to and working between the arms of the U-shaped portions of said cross frame member.

6. A toy on which a child can ride comprising an animal figure, a frame on which said figure is secured, said frame being reciprocable up and down at its rear end to reciprocate the rear portion of the figure up and down and comprising a pair of front to rear members, a cross frame member connecting the rear ends of said front to rear members, said cross frame member having spaced inverted U-shaped members, a main frame on which the first mentioned frame is mounted at its front end, said main frame comprising a pair of front to rear members, and front and rear lateral members and a substantially centrally disposed lateral member connecting said front to rear members, an auxiliary steering frame pivotally secured to the center of said front lateral member, and including a front member pivoted centrally to the main frame front member, a second member located below the centrally disposed lateral member of the main frame, and connecting links between the ends of said second member and said auxiliary frame front member, a rear axle journalled in the front to rear members of the main frame, a front axle journalled in said auxiliary frame, wheels secured on the ends of said axles, steering means including a steering column passing through said centrally disposed lateral main frame member and secured to said second member of the auxiliary frame and projecting through the said figure, and a handle bar secured on the upper end of the column, and means actuated by the rotation of the rear wheels to reciprocate the rear end of the figure supporting frame up and down, said reciprocating means including a crank-like offset portion of said rear axle and a pair of connecting rods journalled on said offset portion and pivoted to and working between the arms of the U-shaped portions of said cross frame member.
